UNITED STATES PATENT OFFICE.

WALTER L. STEVENSON, OF LONG BEACH, CALIFORNIA; BELLE STEVENSON ADDRESSEE AND MINISTRATRIX OF SAID WALTER L. STEVENSON, DECEASED.

WELL CAPPER.

Application filed July 28, 1928. Serial No. 296,060.

This invention relates to improvements in controlling devices for wells, and has for its object to provide an improved device for capping wells to control or stop the flow therefrom. With large and powerful wells it is often a matter of difficulty to stop the flow therefrom, and the present invention is designed to provide a valve with operating devices comprising screws which are powerful enough to draw the valve to closed position under all conditions of flow and pressure. The device includes improved means for fastening the controlling head to the well casing and firmly supporting the same in position at the top of said casing.

Other features of advantage will be apparent from the following description and the accompanying drawings.

In the drawings, Fig. 1 is a front elevation of the device; Fig. 2 is a top plan view; Fig. 3 is a section on the line 3—3 of Fig. 2; Fig. 4 is a detail in cross section.

The dimensions of the various parts may be varied to suit the diameter of the well casing or other local conditions and therefore the present drawings and description are intended only for purposes of illustration.

The head comprises a box like casing A, extended at one side to permit the valve to be opened. This casing has at the bottom a neck 6 threaded to receive a connecting ring or collar D which screws thereon, and the lower end of this ring has an up-turned threaded flange 7 which screws into a collar C having a smaller diameter at the top which screws onto the upper end of the well casing K. The ring D thus has a hook connection with collar C which is very effective in preventing the head being blown off of the well pipe.

The top wall of the casing A is flat, except for a neck 8 threaded to receive a cap E by means of which the well may be sealed if desired.

The valve F consists of a flat plate machined on the top to fit the surface of the casing closely, and strengthened if necessary by cross ribs which meet at a hub 9 from which projects or depends a pivot stud 10 on which is held, by means of nuts P, a yoke or equalizing bar H supported by a washer O. The bar H can pivot on the stud, and it is connected at each end to adjusting screws B which are located at opposite sides of the casing and

are tapped through bosses 11 on the end wall 55 of the casing, the heads being exposed to receive a bar or other tool whereby the screws may be turned. The inner ends of the screws are provided with a plain portion at 12 which extends loosely through slots 13 in the ends 60 of the yoke H, so that the yoke can rock with respect to the screws. The screws are held to the yoke by means of washers L and M at opposite sides of the yoke, and nuts J on the extreme end of the screws, and the surfaces of 65 the yoke bearing against the washers L and M are arched as at 14 to permit the rocking action. The side edges of the valve plate F are rabbeted as indicated at 15 to engage corresponding guides G fastened to the under 70 side of the top of the casing A and forming guides in which the plate F slides.

In use the control head is attached to the top of the well casing by means of the connecting collar C. Then by turning the screws 75 B the valve plate is drawn across the outlet opening in the top of the head and with a close fit the pressure underneath of the fluid will seal the plate against its seat, and effectively cap or close the well. The yoke H 80 will rock or turn to the extent necessary to prevent binding of the valve plate in its guides and the connections permit a certain amount of looseness to enable the valve to seat tightly. The double screws are powerful, and enable the valve to be closed against 85 heavy flow or pressure. The screws of course may be advanced to open the valve as desired. It may be mentioned that the lower neck 6 is of a diameter sufficiently large to permit the 90 valve plate and its connections to be inserted through the same into the casing after which the guides G are attached by the screws N and proper connections made.

It may also be noted that the casing A is 95 cast in one piece without joints which might leak, the necessary connections being screw threaded on the casing neck. Leakage is thus prevented.

The invention is not limited to the particular form shown and described, but various modifications are possible within the scope 100 of the following claims.

I claim:

1. A well capper comprising a valve casing, 105 a sliding valve plate in the casing, a pair of independently operable screws working through a wall of the casing, a stud on the

plate, and a yoke pivoted on the stud and connected to the screws for opening and closing the valve plate.

2. A well capper as in claim 1, the screws 5 being parallel and connected respectively to the ends of the yoke which is pivoted at its middle to the stud.

3. A well capper comprising a valve casing, 10 a slidable valve plate therein having a pivot stud, a cross yoke pivoted on said stud, and independently operable adjusting screws loosely connected to opposite ends of the yoke and extending through a wall of the cas-

ing for opening and closing the valve plate.

4. A well capper comprising a valve casing 15 having means at the bottom to connect it to a well tube, a valve-plate therein, in sliding contact with the top of the casing, said plate having a depending stud, a yoke pivoted on the stud, and independently operable screws 20 connected to opposite ends of the yoke and working through a wall of the casing for closing and opening the valve plate.

In testimony whereof, I affix my signature.

WALTER L. STEVENSON.
